UNITED STATES PATENT OFFICE

135,367

DESIGN FOR A BADGE OR SIMILAR ARTICLE

Mayes Behrman, Atlanta, Ga., assignor to Starr Engraving Company, Houston, Tex., a corporation

Application November 5, 1942, Serial No. 108,709

Term of patent 7 years

To all whom it may concern:

Be it known that I, Mayes Behrman, a citizen of the United States, residing at Atlanta, in the county of Fulton, in the State of Georgia, have invented a new, original, and ornamental Design for a Badge or Similar Article, of which the following is a specification, reference being had to the accompanying drawing, forming a part thereof.

Figure 1 is a front elevational view of a badge showing my new design; and Figure 2 is an edge view thereof.

I claim:

The ornamental design for a badge or similar article, as shown.

MAYES BEHRMAN.
